UNITED STATES PATENT OFFICE.

FRANK BLANDO, OF NEW YORK, N. Y.

PRESS-OPERATING MEANS.

Application filed April 28, 1927. Serial No. 187,407.

This invention relates generally to presses used in connection with the manufacture of artificial flowers, and specifically has to do with new and improved means for actuating 5 the press.

The scope of my co-pending applications is suggested in the accompanying drawings, but in the instant application there is disclosed new and unique means for effecting 10 the vertical reciprocation of certain parts of the well-known press, said means being accurately timed and arranged to bring certain component parts into positions to be operated in an alternative fashion, as will 15 presently appear.

Another object of the invention is the provision of means for supporting certain rotative elements of the structure wherein rigidity and strength are paramount features.

Still another object of the invention is to provide flexible elements directly connected to certain foot-operated means whereby slippage and lost motion may be reduced to a minimum.

With these general objects in view, together with others which will appear as the description proceeds, the invention resides in the novel formation, combination, and arrangement of parts, all as will be described 30 more fully hereinafter, illustrated in the drawings, and particularly pointed out in the claims.

In said drawings:

Figure 1 is a side elevation of a press embodying my improved operating means.

Fig. 2 is a front elevation thereof, the parts being in the same relative positions as noted in said Fig. 1.

Fig. 3 is a plan view of Fig. 1, certain 40 parts of the press being excluded for the sake of clearness.

Fig. 4 is an enlarged elevation illustrating the upper portion of the standard and the means for attaching certain rotative 45 parts thereto; and

Fig. 5 is a detail view of the standard.

Referring now more in particular to the accompanying drawings, wherein like characters of reference denote similar parts 50 throughout the several views, let 5 denote generally a well-known type of press, which embraces the lateral arms 6 and 7 uniting at the top of the press to form the bearing portion 8 adapted to threadedly engage the 55 screw 9, carrying at its lower end the squared member 10 and the usual hand-

wheel 11 at its top portion. Said press is also provided with a base 12 for attachment to suitable supporting means 13, a table for instance. The above structure is 60 similar to that disclosed in my co-pending applications which also includes a guide 14, (see Fig. 2).

As clearly shown in Figs. 1 and 2, a spindle 15 is provided with laterally directed foot portions 16 for attachment to said wheel 11 and through the intermediary of certain mechanism, about to be described, I propose to rotate said spindle to cause the descent of said screw 9 and its 70 squared member 10 for the obvious purpose of contacting certain dies, (not shown), to effect the production of the artificial flowers. Said mechanism is dual in nature, that is, one portion operates said spindle in one 75 rotatable direction and during this performance places in operation the other portion of the mechanism for reversing the rotation of said spindle and eventually returning said squared member 10 to its elevated 80 position shown in Fig. 2.

Said mechanism comprises rotatable members preferably arranged in pairs, each member of the pairs being connected to said spindle 15 and certain foot-operating 85 means respectively. Rising vertically from the rear portion of said table 13 is a standard 17, having its inner edge notched, as indicated at 18, Fig. 5, for engagement with the top of said table. At this point said 90 standard is secured to the table, as indicated at 19, and in addition thereto oblique braces 20 are provided to secure a stable anchorage for said standard 17. As clearly shown in Fig. 5, bosses 21 and 22 project laterally from both sides of said standard, each being suitably apertured for the reception of shafts 23 and 24 carrying pulleys 25 and 26 and also sprocket wheels 27 and 28, said pulley 25 and said sprocket 100 wheel 27 being arranged in pairs and fixedly carried on said shaft 23. The same arrangement is true of pulley 26 and sprocket wheel 28, and thus a unity of operation of each pair is effected.

Referring now to Fig. 1, it will be noted that said pulley 25 is connected to said spindle 15 by means of a flexible member 29, that latter being wrapped around the former and anchored as indicated at 30. To said sprocket wheel 27 is attached a chain 31 which drops to the base of the press where it en-

gages and is secured to another sprocket wheel 32, mounted on shaft 33 suitably journaled at both ends to the table, as indicated at 34. Arranged adjacent to said wheel 32 is a somewhat smaller sprocket wheel 35, that latter being connected to another chain 36 extending to a rod 37 operatively carried by a foot treadle 38 journaled on shaft 39 and suitably supported to said table.

From the foregoing it is apparent that downward pressure on said treadle 38 will exert a pull on said chain 36 causing said wheels 32 and 35 to rotate, said chain 31, 15 winding upon said wheel 32 and rotating in unison said sprocket wheel 27 and 25, causing said flexible member 29 to be wrapped around the periphery of pulley 25 and rotating said spindle 15 and through the intermediary of the screw 9 said squared member 10 descends for contact with certain dies, as aforesaid.

During the functioning of this particular portion of the mechanism, a similar arrangement is being placed in a position to reversely rotate said spindle, as will be pointed out hereinafter.

Obviously the rotation of said spindle 15 by the unwinding of the flexible member 29 causes a second flexible member 40, attached to said spindle, as indicated at 41, to wind upon the latter and this operation rotates said pulley 26 and sprocket wheel 28 causing the chain 42 to exert a 35 rotative pull on another sprocket wheel 43, (see Fig. 2), also mounted on said shaft 33, thus revolving its companion smaller sprocket wheel 44 and through the intermediary of a second chain, attached thereto and the rod 45, a second foot treadle 46 rises to a 40 position previously occupied by said foot treadle 38. It is manifest that a downward pressure on said treadle 46 in the position just described, will reverse the rotative direction of said spindle 15 and elevate said squared member 10 to the position shown in Fig. 2. This operation or operations are continued in alternative form. It will further be noted that throughout the structure 45 the sprocket wheels are each reduced to a diameter somewhat smaller than their companion pulleys, thus providing for a greater amount of flexible member to wind and unwind upon the spindle 15 in view of the increase in travel of the peripheries of said pulleys.

While the present is a disclosure of the preferred embodiment of the invention, it is

to be understood that the invention is not limited thereto, as various changes in the 60 minor details of construction, proportion and arrangement of parts may be resorted to without departing from the spirit of the invention as defined in the appended claims.

I claim:

1. In a press, the combination with a rotatable reciprocatory spindle, a standard, rotatable elements carried by said standard, a flexible member connecting said spindle to one of said rotatable elements, a chain attached to the other of said elements and a treadle operatively connected to said chain and adapted to rotate said elements in unison.

2. In a press, the combination with a 75 rotatable reciprocatory spindle, a standard, rotatable elements mounted in pairs on both sides of said standard, flexible members oppositely wound on said spindle and having their opposite ends secured to one element of each pair, chains connected to each of the other elements of the pairs and treadles operatively connected to said chains and adapted to alternately rotate said elements.

3. In a press, the combination with a rotatable reciprocatory spindle, a standard presenting a pair of apertured bosses, rotatable elements mounted in pairs in said apertured bosses, each pair being adapted to be rotated in unison, flexible members connected 90 to one rotatable element of each pair and having their other ends oppositely wound on said spindle, chains connected to each of the other rotatable elements of each pair and foot treadles operatively connected to the other end of each of said chains and adapted to be manipulated to dispose themselves in alternative operable form.

4. In a press, the combination with a rotatable reciprocatory spindle, a standard, rotatable elements mounted in pairs on both sides of said standard and comprising a paired pulley and sprocket wheel somewhat smaller than said pulley, flexible members oppositely wound on said spindle and having their opposite ends secured to said pulleys, chains connected to each of said sprocket wheels and treadles operatively connected to said chains and adapted to alternately rotate said elements, the rotative movement of said chains being less than the rotative movement of said flexible members attached to said pulleys.

In testimony whereof I affix my signature.

FRANK BLANDO.
